E. PORRO.
CELL DOOR LOCKING DEVICE.
APPLICATION FILED MAY 17, 1916.

1,299,222.

Patented Apr. 1, 1919.

UNITED STATES PATENT OFFICE.

EMILIO PORRO, OF ALBANY, CALIFORNIA.

CELL-DOOR-LOCKING DEVICE.

1,299,222.

Specification of Letters Patent.

Patented Apr. 1, 1919.

Application filed May 17, 1916. Serial No. 98,185.

To all whom it may concern:

Be it known that I, EMILIO PORRO, a subject of the King of Italy, residing at Albany, in the county of Alameda and State of California, have invented certain new and useful Improvements in Cell-Door-Locking Devices, of which the following is a specification.

This invention relates to improvements in locking devices for cell doors and more particularly an arrangement by which such doors may be opened and closed either singly or together from a given station outside of the cell corridor.

Another object of the invention is to so arrange the various mechanisms that all parts are closed thereby preventing tampering by an unauthorized person.

Still another object of my invention is to provide means by which the doors may be locked in their closed position and held in their open position until released from the central operating point.

With these and other objects in view my invention consists in the novel construction, combination and arrangement of parts herein illustrated and more specifically pointed out in the appended claims.

Reference being had to the accompanying drawing forming a part of this specification,

Figure 1 is a view in front elevation showing several cell doors, together with the operating mechanism of the same.

Fig. 2 is an enlarged view in plan showing the mechanism associated with one door.

Fig. 3 is a view in section on 3—3, Fig. 2.

Fig. 4 is a view in section on 4—4, Fig. 2.

Fig. 5 is a view in elevation of one of the selector mechanisms by which the various doors are connected to the operating shaft.

Fig. 5^a is a view in elevation of one of the door latch-lifting devices.

Fig. 6 is a view in elevation of the member by which the locking mechanisms are lifted and by which the same are locked when the door is closed.

Fig. 7 is a view in vertical section through the channel on one side of each door showing the manner of locking the latter.

Fig. 8 is a view in section through one edge of the door and the abutment thereof.

Fig. 9 is an enlarged sectional view

through the operating shaft showing the yoke member for imparting longitudinal movement to the said shaft.

Fig. 10 is an enlarged view in plan of the end of the shaft by which the various doors are operated.

Referring to corresponding parts in the several views by the same numerals of reference, 1 denotes the front wall of a row of cells, the openings therein being closed by doors 2. These doors may be of any preferred construction and are provided with the hangers 3 carrying grooved wheels 4 by which the doors are suspended on a suitable track 5.

On the upper end of the hangers is mounted a strip 6 extending the length of the door and provided with an inclined end 7 adjacent to which is a notch 8 for the purpose hereinafter described.

Along one side of the door and forming an abutment for the latter is a jamb 9 formed of the U-section 10, and the web 11, the latter being riveted or otherwise fastened. The cell wall projects into a rabbet in the side of the door 2, thereby covering the crack between the door and its abutment. The portion 10 is provided with a slot 12 wherein is a bar 13 having a limited longitudinal motion with respect to the member 9. The U-shaped portion 10 is provided with a transverse opening 14 through both walls, and the door 2 is provided with a hook-shaped catch 15 adapted to pass through this opening. This catch has an inclined face which may engage member 13, raising the latter, which then falls behind the shoulder on the catch, thus holding the door in its closed position until member 13 is again lifted.

Member 13 extends upwardly past the angle 5 which forms a track for the door and the upper end is provided with the lateral extension 16, the inside of which is, under certain conditions, adapted to drop into the slot 8 of member 6. When the extension is in this slot it will be apparent that the door is held in two places, at the upper portion by virtue of 16 entering the slot 8 and at the center by means of the shoulder on the latch 15 being engaged back of the lower end of member 13. A suitable guide 16' is provided

at the upper end of bar 13 to prevent side bending thereof in case of attempts to force the door.

On the hanger 3 adjacent the inclined 5 end of member 6 is provided a bracket 18 having the forwardly projecting fingers 19 through the medium of which the door is moved from its open to its closed position, and vice versa. The upper portion of the 10 door and the associated mechanism is inclosed in a rectangular case, denoted in general by 20. This case being so arranged that the various mechanisms described are completely inclosed, thereby preventing any 15 unauthorized person from tampering with the same. The front of this casing, denoted by 21, is longitudinally slideable so that any portion of the mechanism is readily accessible.

20 Mounted in the front of the casing thus formed is a shaft 22 which is both revolvably and slidably journaled at suitable intervals. On this shaft for each door are keyed two members denoted by 23 and 24, the former 25 member being provided with means whereby all of the doors, or any particular door may be selected and moved longitudinally while the latter has means whereby the latches of the various doors may be lifted when said 30 doors have been selected for opening, but capable of preventing the raising of the latches of those doors which have not been selected. Each of the members 23 is shown as provided with a conical shaped portion 35 25, a cylindrical portion 26, and a collar 27, but the shape is immaterial, being a mere structural detail. The collar 27 is provided with two wards 28 and 29. The wards 28 on all of the members 23, project from said 40 members at the same angle, but the wards 29 project at different angles, the former being used when all the doors are opened simultaneously, while the latter is used to selectively open any individual door.

45 When the door is in its closed position the collar 27, together with its ward, are spaced between the fingers 19 but the distance between these fingers is such that the collar has some travel before the wards engage the fingers 19. Member 24 is provided with two projecting lugs 30 which for any door are spaced in the same angular relation as the wards 28 and 29 of that door, and each of these lugs is provided with the 50 inclined faces 31 adapted to contact with the underside of the hook 16. Also above these locks is a shoulder 32 which when the doors are all to be held closed may be brought into contact with the top of hook 16, thus preventing the latter from being raised.

The strip 6 is provided with an additional notch 36 and pivotally mounted to one side of the door is a latch 37 extending outwardly 65 from the wall and normally resting on the

shaft 22. This latch is provided with a depended portion 38 which is adapted to enter the notch 36 when the door is moved to its open position. The shaft 22 is operated by means of the several levers 40 and 41, the former being arranged to rotate the shaft while the latter is arranged to move it longitudinally.

To rotate the shaft there is provided a tooth sprocket gear 42 keyed on the same 75 shaft with lever 40, this sprocket being connected by means of a chain 43 in a tooth gear 44, mounted on a square shaft 45. This shaft is pivotally mounted in a bearing bar 46 and extends into a square opening in the end of shaft 22, whereby the latter is slideable on shaft 45 but is rotated by the latter.

The end of shaft 22 is provided with a grooved collar 46 about which is a yoke 47, this yoke being slidably mounted on a bar 49 positioned parallel to shaft 22 and being provided on the underside with ears 50 between which is pivotally mounted the lever bar 41. The latter is pivotally mounted to the frame-work of the cells as shown at 52 and working over a stationary segment 53. Adjacent the lever 41 is a tooth segment 54, each tooth corresponding to a given operative position of shaft 22. 95

Having thus described the various details of my invention its operation is as follows:—

First, if a given door is to be opened, lever 40 is moved until the pawl drops in 100 the notch corresponding to that door. Then through the chain 43, sprocket 44 is rotated, turning with it the shaft 22 so as to bring the ward 29 of the selected door into alignment with the fingers 19 of that door. At 105 the same time the member 30, in alignment with ward 29, is positioned under the hook 16 of that door, the handle 41 is then moved so as to slide the shaft 22 longitudinally, the first movement of the shaft causing the 110 inclined faces of member 30 to raise the hook 16 and thereby the member 13, which in turn lifts this member from the notch 8 and from back of the shoulder on catch 15.

During this lifting movement the ward 115 29 has been moving from one finger 19 to the other so that by the time the door is released the ward has contacted with the second finger 19 thereby moving the door in the direction of the arrow, which movement 120 is continued as long as lever 41 is rotated. A stop is provided for the door so in its extreme left position the notch 36 is positioned under the latch 37. Thus if it is desired to have the door held in its open position lever 125 40 is again rotated to its extreme position whereby the wards clear the fingers 19 thus allowing the shaft to be moved to the right without carrying the door with it and as the member 23 is moved from under the bar 130

37, the lock on the latter drops into the notches 36 and thereby holds the door against being closed. In closing the door, lever 41 is shifted in the opposite direction, 5 causing member 30 to lift latch 37, after which the door moves to closed position.

If it is desired to open all the doors simultaneously, handle 40 is rotated to the position in which the wards 28 aline with the corresponding finger 19 of each door so that when the handle 41 is moved to slide to the door longitudinally, all doors are opened. The doors are closed by the opposite move of handle 41, and after being closed the 10 shaft 22 is rotated to the position where the wards clear the fingers of all doors. When the handle 40 is again moved, the position is reached to impart to the shaft a slidably longitudinal movement whereby the shoulder 32 is brought over the top portion of hook 16. The handle 41 is locked in this position by means of a suitable pawl and slot arrangement, and in this manner it will be impossible for the latch bar 13 to be upraised.

25 While I have shown and described the preferred embodiment of my invention it will be understood that minor changes may be made in form and detail without departing from the scope of the claims.

30 What I claim as new and wish to cover by Letters Patent is—

1. The combination with a plurality of sliding doors, a shaft slidably and rotatably mounted above said doors, selectors attached 35 to said shaft adjacent each door, wards on said selectors, fingers extending from said doors, means for rotating said shaft to bring the wards into engagement with said fingers, and means for longitudinally shifting said 40 shaft to impart movement to the door by means of the engagement of the wards and fingers.

2. The combination with a plurality of sliding doors, of abutments for said doors each having a longitudinal channel, latch bars slidably mounted in said channels, catches on the doors adapted to engage the latch bars, a shaft slidably and revolvably mounted above said doors, selectors attached 45 to said shaft adjacent each door, wards on said selectors, fingers extending from said doors, means for rotating said shaft to bring the wards into engagement with said fingers,

and means for longitudinally shifting said shaft to impart movement to the doors by 55 means of the engagement of the wards and fingers.

3. The combination with a plurality of sliding doors, a latch for each of said doors, a shaft revolvably and slidably mounted 60 above said doors, selectors on said shaft each having a common ward and a selector ward, the common wards of all of the selectors being disposed in the same angular relation and the selector wards of the selectors being disposed at different angles with respect to the common wards, means on each of said doors adapted to be engaged by said wards by rotation of said shaft, and means for shifting said shaft longitudinally to impart movement to the selected door or doors by means of engagement of the wards with respect to the doors.

4. The combination with a plurality of sliding doors, a shaft slidably and revolvably mounted above said doors, selectors attached to said shaft, radially extending wards on each of said selectors, one ward of each selector being in alinement, and the other ward being at a different angle on each selector, 75 fingers extending outwardly from said doors adapted to be engaged by said wards, and means for rotating the shaft to selectively engage the wards with the doors, and means for sliding the shaft longitudinally to 80 impart movement to the doors by means of the engagement of the wards therewith.

5. The combination with a plurality of sliding doors, abutments for each of said doors, each abutment having a vertical opening, latch bars slidably mounted in said openings, and each provided with a lateral extension at its top, catches on the doors positioned to engage said latch bars, a shaft 90 slidably and revolvably mounted above said doors, selectors attached to said shaft adjacent each door, wards on said selectors, fingers extending from said door, means for rotating said shaft to bring the wards into selective engagement with said fingers, and means for longitudinally shifting said shaft 95 to impart movement to the door by means of the engagement of the wards and fingers.

In testimony whereof I affix my signature.

EMILIO PORRO.
